UNITED STATES PATENT OFFICE.

PAUL VOGES, OF CHICAGO, ILLINOIS, ASSIGNOR TO MANZ ENGRAVING COMPANY, OF CHICAGO, ILLINOIS, A CORPORATION OF ILLINOIS.

DESIGN FOR A DISPLAY-CARD OR SIMILAR ARTICLE.

50,594.

Specification for Design.

Patented Apr. 10, 1917.

Application filed December 3, 1915. Serial No. 64,920. Term of patent 3½ years.

To all whom it may concern:

Be it known that I, PAUL VOGES, a citizen of the United States, residing at Chicago, in the county of Cook and State of Illinois, have invented a new, original, and ornamental Design for a Display-Card or Similar Article, of which the following is a specification, reference being had to the accompanying drawing, forming part thereof.

In the drawing—

card or similar article showing the new design.

Fig. 2 is an edge view of the same.

I claim:

The ornamental design for a display card or similar article as shown.

PAUL VOGES.

Witnesses:

JOHN W. C. MAN,
A. P. REGITZ.
